FLUSH FLOOR MOUNTED SAFETY LATCH FOR HYDRAULIC LIFTS

Ion V. K. Hott and David M. Goldzwig, Dayton, Ohio,
assignors to **The Joyce-Cridland Company, Dayton,**
Ohio, a corporation of Ohio

Application September 9, 1954, Serial No. 454,890

3 Claims. (Cl. 187—8.5)

The present invention relates to flush floor mounted safety latches for hydraulic lifts and more particularly to a safety device the effectiveness of which is increased by the weight of the load upon it, although not necessarily so limited.

An object of the invention is the provision of a safety latch for hydraulic lifts which is strong and sturdy and one which is simple in construction, easy and economical to manufacture, easy to operate and which is substantially fool-proof.

A further object of the invention is the provision of a safety device for a hydraulic device which remains in operation, allowing only travel in one direction until released.

A further object of the device is the provision of a safety latch for a hydraulic lift which is foot actuated, and so placed and operated that it cannot be accidentally tripped.

A further object of the invention is the provision of a safety latch which can be applied to a hydraulic lift for servicing all makes of cars with no other mechanical adjustments.

A further object of the invention is the provision of a safety latch for a hydraulic lift, all parts of which are substantially at or below floor level.

A further object of the invention is the provision of a safety latch which functions automatically at all times when the lift is in raised position, which has to be manually disengaged and which recocks automatically.

Other objects and advantages reside in the construction of parts, the combination thereof and the mode of operation, as will become more apparent from the following description.

In the drawings, Figure 1 is a perspective view of one form of latch showing a portion of floor broken away and showing concealed portions in dotted lines.

Figure 2 is a fragmentary vertical cross section taken substantially on the line 2—2 of Figure 1, showing the latch in operative position.

Figure 3 is a fragmentary vertical cross section showing the latch in its tripped position.

Figure 4 is a perspective view similar to Figure 1 showing a modified form of latch.

Figure 5 is a fragmentary vertical cross sectional view, taken substantially on the line 5—5 of Figure 4.

Figure 6 is a fragmentary view of the device of Figure 4 partly in cross section and showing the parts in tripped and inoperative position.

Figure 7 is an exploded view of the pawl or detent member and the weight associated therewith.

Referring more in detail to the drawings, a pair of vertically disposed cylinders or supporting members 10 and 11 are set in a concrete or other floor 12 and extend throughout their entire length below the floor. A channel member 14 is positioned at the lower ends of members 10 and 11. The lower ends of these members 10 and 11 fit within the channel and the member 14 operates as a locating and aligning element.

2

The upper ends of the cylinders or support members 10 and 11 are provided with packing glands 16 which are flush with the floor. Sliding within the cylinder members 10 and 11 are a pair of cylindrical lifting elements or pistons 18. These elements are propelled upwardly by a hydraulically operated means (not shown). The lifting members 18 are provided at their upper ends with a pair of horizontally disposed frame engaging members or rails 20, disposed in parallel relationship, the distance between them being such that the members 20 are in a proper position to contact the frame of an automobile. The preceding device is conventional in hydraulic lifts and has been shown merely for the purpose of illustration. The arrangement of this mechanism and the construction thereof may be varied depending upon the particular requirements and the available parts.

A housing box 22 is set in concrete at flush floor level and is provided with a pair of openings 24 and 26 located in alignment in its top and bottom walls. A pair of stationary cylindrical housing members 28 and 29 are located under the floor and may be secured at intervals if desired to the members 10 and 11 respectively. The housing boxes 22 and 23 are secured to the members 28 and 29 respectively. The structure is duplicated in the members 11 and 29. Slidable within the cylindrical member 28 and through the openings 24 and 26 is a rack member 30, provided on its exterior surface with a series of wedge-shaped teeth 32.

A shaft 34 is journalled in opposite vertical walls of the housing member 22, and carries a pinion member 36 provided with teeth 38. The teeth 38 of the pinion 36 mesh with the teeth 32 of the rack member 30. The shaft member 34 is journalled in one vertical wall 37 and extends through the opposite wall of the housing 22 and 25 extends further to the housing 23. The housing 23 is attached to the other cylindrical supporting member 11. The racks 30 are fixedly attached to the frame engaging members 20, so as to be raised and lowered therewith.

The housing 22 contains pinions 36, not shown. The pinions 36 operate in unison as a pair, moving concomitantly to keep the upper travel of the racks 30 synchronous and to keep the members 20 at the same level in all positions of their upward and downward movement. This device may be called an equalizer.

The safety latch is housed within the box member 22. A pivot or fulcrum rod 42 is journalled in the vertically opposite walls of the box. Rigidly connected to the shaft 42 is a detent or pawl 44 and a counterweight member 46. The detent 44 and the counterweight member 46 are joined by a portion 49, that is, the detent 44 and the counterweight member 46 are integral. The combined weight of members 44 and 46 may swing through dead center. When on one side of dead center the weight 46 urges the detent into engagement with the rack 30 and 50 when on the other side of dead center the combined weights of members 44 and 46 hold the detent out of engagement with the rack. The detent is provided with a tooth 48. The tooth 48 is provided with upper and lower surfaces so pitched as to mesh within the space or notch between two consecutive teeth 32. The upper surface 48a of the tooth 48 has the same angle as the slope of the underside of a tooth 32. The underside 48b of the tooth 48 has an angle that is steeper than the slope of the upper side of a tooth 32. Upward movement of the rack is allowed and downward movement prevented. The rack may move upwardly by stages, and rest at any point without slipping back. The weight member 46 has an integral arm 50, so positioned that the counterweight 46 and the arm 50 are on opposite sides of the fulcrum rod 42. A foot pedal or operating arm 52 is mounted on a pivot or fulcrum rod 54 and is provided with an arm 56. The members 52 and 56 are positioned on opposite sides of

the fulcrum rod 54 and the arm 56 is adapted to engage and actuate the arm 50. When the foot pedal 52 is operated upwardly, the arm 56 will rock against the arm 50 causing the weight 46 to swing in a counterclockwise direction, as viewed in Figure 2, through dead center into the position shown in Figure 3. As the counterweight 46 is swung, the shaft 42 on which it is rigidly connected is rotated and the detent 44 is rocked in a counterclockwise direction as shown in Figure 2 into the position shown in Figure 3, and the tooth 48 is disengaged from the teeth 32 of the rack 30. When the foot pedal is lowered so as to be flush with the floor, the arm 56 will then rock into engagement with the main body of the weight 46 to actuate the weight 46 and the pawl 44 through dead center, to thereby cause the pawl to drop into engagement with a tooth 32.

In operation, when the foot pedal 52 is pressed downwardly, the tooth 48 is engaged with the teeth of the rack 30. The weight 46 is in the position shown in Figure 2. The foot pedal 52 is positioned so that a space remains between it and the wall of the housing 22 so that the toe of an operator may be inserted underneath it to operate it upwardly. When this is done, the parts assume the positions shown in Figure 3. The detent 44 is out of engagement with the teeth 32 and there is nothing to prevent the downward movement of the rack 30. As long as the parts are in the position shown in Figure 2 with the detent 44 in engagement with a tooth of the rack 30, the force of the counterweight 46 and the shape of the tooth 48 together with the cooperating portion of the teeth 32 hold the tooth in its engagement. The force of the weight of a car will react with the slanting engaging upper surfaces of the teeth 48 and 32 to further reinforce the engagement of the detent 44 by the teeth 32. It will thus be seen that the weight of a car reinforces the safety factor of the latch and increases its effective engagement.

The upper surface of the foot pedal 52 is substantially flush with the floor level and its accidental tripping is precluded.

The device is extremely sturdy and of such simple construction that its manufacture is inexpensive and yet the arrangement of parts is such that the device is practically fool-proof.

In the device shown in Figure 1, a pair of lifting members 18 are shown. In the modification shown in Figures 4 to 6, a single cylindrical element 60 is mounted on a standard 62 and a single lifting element 64 is shown. The upper end of the lifting element 64 carries an H-shaped member 66, the two rails 68 of which constitute the automobile frame engaging elements. A rack member 70 is secured at its upper end to the H-shaped member and extends through the casing 72 and into the tubular member 73.

The cylindrical member 60 reaches to floor level and in this area is provided with a latch housing 72. The rack member 70 is provided with a vertically disposed series of aligned openings 74. The lower portion of the housing 72 is provided with a lower opening 76, into which opening the tubular member 73 projects. A shaft 78 carries a detent 80 and a weight member 82, both rigidly connected to it. A shaft 84 carries a toe pedal or lever 86 and a rocking arm 88. All of this latch mechanism is similar to that shown in Figures 1, 2 and 3, with the

exception of the rack member 70, which is provided with openings 74 in place of the teeth 32. As clearly seen in Figure 6, the safety latch recocks automatically whenever member 66 is lowered to rest on the floor. A tooth 90 on the detent 80 engages in the opening 74 of the rack.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described our invention, we claim:

1. A safety device for a vehicle lift having means for raising a vehicle from a floor, said lift having a member provided with indentations moving with the lift, including the combination of a pawl mechanism having an operative position and an inoperative position, said pawl mechanism passing through dead center when moving from one position to the other, means for mounting the pawl mechanism below floor level so as to engage the indentations when in operative position, and foot operated means located on the floor level when the pawl mechanism is in operative position and positioned below a portion of said vehicle raising means, said foot operated means engaging said pawl mechanism to actuate the same, said foot operated means being movable into a position above floor level to actuate the pawl mechanism from operative position into inoperative position, said portion of said vehicle raising means when lowered to the floor actuating the foot means into floor level position to thereby recock the safety device.
2. A safety device according to claim 1, wherein the floor is provided with a cavity in which the foot operated means is mounted, said cavity providing a clearance whereby the foot operated means may be raised by the sole of a shoe.
3. A safety device according to claim 1, wherein the foot operated means includes a pedal member normally located flush with the floor, pivot means for mounting said pedal member, and an arm directed downwardly from the pedal member and integral therewith, said arm engaging an extension of the pawl mechanism to actuate the pawl mechanism out of contact with the indentations when the pedal member is moved out of floor flush position, said arm engaging a portion of the pawl mechanism to swing the pawl mechanism through dead center into operative position when the pedal member is returned to flush position.
